UNITED STATES PATENT OFFICE

96,361

DESIGN FOR A COMBINATION CLOTHES AND HAT HOLDER

Everett Lorne Whenham, Los Angeles, Calif.

Application September 11, 1933, Serial No. 49,234

Term of patent 14 years

To all whom it may concern:

Be it known that I, Everett Lorne Whenham, a subject of the King of England, residing at Los Angeles, in the county of Los Angeles and State of California, have invented a new, original, and ornamental Design for a Combination Clothes and Hat Holder, of which the following is a specification, reference being had to the accompanying drawing, forming part thereof.

Fig. 1 of the drawing is a perspective view of my combination clothes and hat holder, with the curtain thereof partly open, and

Fig. 2 is another perspective view thereof, with the curtain wholly open to facilitate the illustration.

In the drawing:

A is a clothes hook,
B is a lady's hat holder,
C is an inclosing curtain for the latter, and
D is a man's hat holder.

I claim:

The ornamental design for a combination clothes and hat holder, as shown and described.

EVERETT LORNE WHENHAM.
